UNITED STATES PATENT OFFICE.

JOHN P. BADENHAUSEN, OF PHILADELPHIA, PENNSYLVANIA.

STEAM-SUPERHEATING SYSTEM FOR MARINE BOILERS.

Application filed March 25, 1919. Serial No. 285,028.

To all whom it may concern:

Be it known that I, JOHN P. BADENHAUSEN, a citizen of the United States, residing in the city of Philadelphia, county 5 of Philadelphia, State of Pennsylvania, have invented certain new and useful Improvements in Steam-Superheating Systems for Marine Boilers, of which the following is a specification, reference being 10 had to the accompanying drawings, forming a part hereof.

My invention relates to a superheating system as applied to marine boilers and has for its main object the constructing and 15 arranging of a superheating system whereby the heating units thereof may be located in the hottest part of the combustion chamber, rather than nested in the flue tubes, in order that a greater degree of superheat may be 20 secured.

Another object is to so construct and arrange the system whereby steam shall at all times remain in the units of the systems, notwithstanding that the throttle at times 25 may be closed, with the effect of protecting the units from the burning and other destructive effects of the hot gases acting upon the units.

Another object is to secure the safety 30 valve to the main steam line, leading from the superheating units between the latter and the throttle in order that the safety valve shall act as a relief means for any possible excess pressure that may arise in 35 the heating units at the time when the throttle is closed.

It is the object of my invention to locate the superheating units within the chamber through which the hot gases from the fire 40 box pass before they enter the fire tubes and also to avoid the disadvantages arising in the old form of superheating system wherein the superheating units are nested within the fire tubes of the boiler.

For the purpose of carrying out my invention I have shown in the accompanying drawing one embodiment thereof and referring to said drawing in which reference characters are used to designate correspond- 45 ing parts in the various figures.

Fig. 1 is a longitudinal sectional view through a conventional type of marine boiler showing the adaptation of my improvement thereto;

Fig. 2 is a transverse sectional view show-

ing the disposition of the superheating units in the hot gas chamber, taken on line 2-2 of Fig. 1;

Fig. 3 is a horizontal sectional view taken on line 3-3 of Fig. 1 including a 60 top plan view of the superheating units.

Fig. 4 is a transverse sectional view taken on line 4-4 of Fig. 1 showing the superheating units in vertical elevation.

Referring now more particularly to the 65 drawing I have shown thereon a usual form of marine boiler 1 the upper portion of which is provided with a plurality of fire or flue tubes 2 and in the lower portion of which are located the usual fire boxes 3 in 70

which are included the usual grates 4 and the bridges 5. At the rear portion of the boiler are also located the hot gas combustion chambers 6. The superheating system, 75

forming the subject-matter of my invention, comprises conduits 7 leading from the upper interior portion of the boiler to compartments 8 in headers 9 located in the combustion chamber 6. From the compartments 8 of these headers 9 lead banks of 80

tubes 10 in looped or inverted U-shape or form extending to the upper portion of the chambers 6 and returning to second headers 11 located adjacent to the first headers 9.

A second set of tubes 12 leads from these 85 headers 11 to the second compartments 13 of the headers 9 from which finally lead conduits 14 to the outside of the boiler, the same passing through the thimbles 15 trav- 90

ersing the water leg 16 of the boiler 1. By such means the steam in passing successively through these groups of tubes receives progressive superheat. The external 95 end of the conduits 14 are provided with fittings 17 from which the steam lines 18 lead upwardly to a connecting fitting 17' and thence by a steam line section 17" and a "cross" fitting 19 secured to the top of the boiler 1. This "cross" fitting may be 100

surmounted by any suitable form of safety valve 20 and may be connected through a lateral port thereof to the main steam line 21 leading to a throttle of any suitable form.

As the gases or volatile constituents pass 105 from the fire box through the combustion chambers 6 at which time they are practi- cally at their highest temperature, heat will be more readily and efficiently extracted therefrom, for heating the steam passing

105

110

through the loops or units 11 and 12, prior to the entry of the gases into the fire tubes 2 of the boiler.

It will be thus seen from the above that 5 the steam flowing into the open inlet ends of the pipes 7 passes into the header 9 to the units or tubes 10 which extend uprightly in the combustion chamber 6 at points where the gases from the fire boxes are at about 10 their highest temperature so that the steam is more effectively superheated than if the tubes were disposed within the fire tubes of the boiler. Furthermore, it will also be seen from the above by so arranging the tube 15 units in the combustion chamber in the passage of the hot gases or volatile constituents as they issue from the fire boxes, rather than nesting the units within the fire tubes, that free and unimpeded passage of the hot gases 20 through the fire tubes is permitted. This also permits the use of smaller fire tubes, whereby increased volume capacity of the boiler is obtained. In any form of superheating system where the heating units are 25 disposed within the fire tubes it necessarily follows that to be of any utility it would require or necessitate making the fire tubes of appreciably larger diameter in order to enclose such units as well as to provide the 30 requisite passage for the flue gases for the proper operation of the boiler. This obviously reduces the volume capacity of the boiler. Moreover, by heating the units within the fire tubes increased resistance is offered to the passages of the flue gases, a 35 disadvantage absolutely avoided in the improvement herein described.

Therefore, by locating the superheating units in the chambers 6 all of the disadvantages mentioned are overcome and, a higher degree of superheat is also obtained than that available in the fire tubes.

In the event that the throttle is entirely closed the steam will still remain in the superheating system to protect the same from the destructive effects of the hot gases and in case that the pressure within the superheating units is increased considerably such pressure will be released by the safety valve, 45 connected in the steam line, and permit the inflow of fresh steam into the superheating units, thereby continuing the protection thereof. The fitting 11 is merely secured to the top of the boiler and does not communicate therewith except through the superheating system.

In addition to the above a small connection 50 22 in which is provided a hand valve 23 is adapted to establish connection from the fitting 17 to the water leg 16 of the boiler. The purpose of this attachment is that when first starting up the boiler the valve 23 may be initially opened to permit the water in the boiler to flow through the connection 22 into 55 the fitting 17 to the pipe 14 and finally into

the tubes 10 and 12 and conduit 7, as well as the vertical pipe 18 leading from the fitting 17, whereby the hot gases shall, in the initial operation of the boiler, rapidly aid in generating steam from the water enclosed in the units 10 and 12. During the normal operation of the boiler, however, the valve 23 is closed.

While I have disclosed one embodiment of my invention it is to be understood that the latter is not limited to the particular details herein described and shown but that it may comprehend other and equivalent structures as may come within the spirit of my invention and the scope of the appended claims.

Having described my invention what I claim as new and desire to secure by Letters Patent is:

1. In a steam generating system comprising a boiler having fire tubes, a fire box, a bridge, a combustion chamber, a water leg, and a crown sheet at the upper end of said combustion chamber, the combination of a header located in said combustion chamber parallel and close to, and just below the top of said bridge, a second header provided with two chambers and arranged close and parallel to said first header, a conduit leading from the steam space in said boiler directly through said crown sheet to one of said compartments of said second header, a series of tubes extending from said compartment upwardly in said combustion chamber to a point close to said crown sheet and thence downwardly past the open ends of said fire tubes to said first header, a second series of tubes leading from said first header upwardly past the open ends of said fire tubes to a point near said crown sheet and thence downwardly to the second compartment of said second header and a conduit leading from said second compartment rearwardly through the said water leg to the rear of the boiler and thence to the point of consumption.

2. In a steam generating system comprising a boiler having fire tubes, a fire box, a bridge, a combustion chamber, and a crown sheet at the upper end of said combustion chamber, the combination of a header located in said combustion chamber parallel and close to, and just below the top of said bridge, a second header provided with two chambers and arranged close and parallel to said first header, a conduit leading from the steam space in said boiler directly through said crown sheet to one of said compartments of said second header, a series of tubes extending from said compartment upwardly in said combustion chamber to a point close to said crown sheet and thence downwardly past the open ends of said fire tubes to said first header, a second series of tubes leading from said first header upwardly past the open ends of said fire tubes.

to a point near said crown sheet and thence downwardly to the second compartment of said second header, a conduit leading from said second compartment rearwardly to the outside of the boiler and thence to the point of consumption, and means operative when the superheated steam is not being drawn off for consumption and the temperature of the steam is high to cause a flow of steam 10 from said boiler through said tubes.

3. In a steam generating system comprising a boiler having fire tubes; a fire box, a bridge, a combustion chamber, a water leg, and a crown sheet at the upper end 15 of said combustion chamber, the combination of a header located in said combustion chamber parallel and close to, and just below the top of said bridge, a second header provided with two chambers and arranged 20 close and parallel to said first header, a con-

duit leading from the steam space in said boiler directly through said crown sheet to one of said compartments of said second header, a series of tubes extending from said compartment upwardly in said combustion 25 chamber to a point close to said crown sheet and thence downwardly past the open ends of said fire tubes to said first header, a second series of tubes leading from said first header upwardly past the open ends of said 30 fire tubes to a point near said crown sheet and thence downwardly to the second compartment of said second header, and a conduit leading from said second compartment rearwardly through said water leg to the 35 rear of said boiler and thence to the point of consumption.

In witness whereof I hereunto set my hand this 24th day of March, 1919.

JOHN P. BADENHAUSEN.
